UNITED STATES PATENT OFFICE.

JESSE F. BILLMAN, OF LITCHFIELD, ILLINOIS.

SEWING-MACHINE FAN.

SPECIFICATION forming part of Letters Patent No. 519,227, dated May 1, 1894:

Application filed November 7, 1893. Serial No. 490,250. (No model.)

To all whom it may concern:

Be it known that I, JESSE F. BILLMAN, a citizen of the United States, residing at Litchfield, in the county of Montgomery and State of Illinois, have invented a new and useful Sewing-Machine Fan, of which the following is a specification.

My invention relates to a fan for sewing machines, adapted to be applied to a rotatory member, such as a pulley or wheel, to provide a draft during the operation of the machine; and the objects in view are to provide means for the adjustment of the members of the fan to increase or diminish the power of the draft produced thereby, and to provide simple and adjustable means for attaching the device to a wheel or pulley.

A further object of the invention is to provide means for adjusting or changing the curvature or deflection of the wings to project the current of air in any desired direction.

Further objects and advantages of this invention will appear in the following description, and the novel features thereof will be particularly pointed out in the appended claims.

In the drawings: Figure 1 is a side view of a fan embodying my invention, applied in the operative position to a sewing machine. Fig. 2 is a sectional view of the same. Fig. 3 is a detail view of one of the wings. Fig. 4 is a similar view of the spider.

Similar numerals of reference indicate corresponding parts in all the figures of the drawings.

The fan comprises essentially the longitudinally adjustable members 1, each consisting of a wing 2, and a perpendicularly-disposed web or flange 3. These webs or flanges are adapted to be arranged in contact in parallel planes, as shown clearly in Fig. 2, and they are provided with longitudinal slots 4, for the reception of an adjusting-bolt 5, provided with a nut 6. A washer 7 is arranged between the head 8, of this bolt and the adjacent surface of the outer web or flange 3. The webs or flanges are provided at their free edges, or the edges opposite to the wings 2, with lips 9, whereby when the web or flange of one member is arranged within the web or flange of the other member, it fits between

the wing and said lip, and thus holds the two members from angular displacement.

10 represents a spider, having the inwardly-divergent legs 11. These legs are preferably formed in pairs, the members of each pair being arranged diametrically opposite each other and of a single bar. The legs are capable of angular adjustment around the bolt 5, by which they are secured to the fan, and they are provided at their outer ends with concaved terminals or feet 12, to engage the inner convex surfaces of the rim of a wheel or pulley, as shown clearly in Fig. 1. 15 These divergent legs are formed of spring steel, whereby they may be contracted to fit wheels or pulleys of different sizes, and they are held by this spring action from accidental displacement. The members are constructed of block tin, or similar pliable sheet metal (the wings being integral with the webs or flanges) and the wings may be bent or shaped to change their deflection and direct the current of air as desired to suit the position of 20 the operator when sitting in the preferred position. This is rendered necessary by the fact that different operators assume different positions while at work. Furthermore, by means of the slots 4 the wings may be separated more or less to give the desired force to the current of air.

Various changes in the form, proportion and the minor details of construction may be resorted to without departing from the principle or sacrificing any of the advantages of this invention.

Having described my invention, what I claim is—

1. A fan for sewing machines, having twin longitudinally-slotted wing-bearing members, a spider having legs to engage the rim of a wheel or pulley, and a common bolt for connecting the wing-bearing members and the legs of the spider, whereby the former are longitudinally and the latter are angularly adjustable, substantially as specified.

2. A fan for sewing machines having twin longitudinally-adjustable members, pliable wings carried by said members and adapted to be adjusted or altered in curvature deflection, and means for securing the fan to a rotary member of a machine, substantially as specified.

3. A fan for sewing machines having a spider consisting of divergent spring-metal legs provided with concaved terminals or feet to engage the inner convex surfaces of the rim of a pulley or wheel each pair of opposite legs being formed of a continuous strip of metal, whereby all of the legs may be secured by a single bolt to provide for relative angular adjustment, substantially as specified.
4. A fan for sewing machines comprising twin adjustable wing-bearing members provided with webs or flanges having longitudinal slots, an adjusting bolt engaging said slots, and a spider comprising divergent

spring-metal legs mounted upon and held in place by said adjusting bolt, provided with concaved terminals or feet to engage the rim of a wheel or pulley and capable of angular adjustment around said bolt, substantially as specified.

In testimony that I claim the foregoing as my own I have hereto affixed my signature in the presence of two witnesses.

JESSE F. BILLMAN.
